GOLF BAG

Irving H. Filler, Washington, D. C., and Victor H. Olmsted, Rockville, Md.

Application January 29, 1948, Serial No. 5,068

4 Claims. (Cl. 150—1.5)

1

The present invention relates to a uniquely constructed golf bag provided with means for receiving and carrying a thermos jar container for hot or cold beverages for consumption by the player.

It is well appreciated that the game of golf is played on a golf course embracing eighteen holes and the average golfer usually covers about five miles in the playing of an eighteen hole course.

A great many golf courses are devoid of drinking fountains and often extend to points remote from the clubhouse or any such location where drinking water or other beverages are obtainable.

The game of golf is quite universally played and it is played throughout all seasons of the year. In the heat of summer the players often become extremely thirsty and crave a refreshing cold drink. This craving often adds to the mental hazard to say nothing of the physical discomfort encountered by the player. In the cold of winter the craving for a hot cup of coffee is equally pronounced.

In order to provide the instrumentalities for supplying the beverage needs to the players, the present invention contemplates a golf bag structure provided with means for accommodating a thermos jar beverage container adapted to be held in a position for the ready dispensing of the beverage therefrom without removal of the thermos jar container from its assembled position in the golf bag and without in any way disturbing the normal use of the golf bag for carrying the player's clubs and equipment.

It is, therefore, the broad object of the present invention to provide a golf bag with a unitary thermos jar supporting means so positioned as to permit the dispensing of beverages from the thermos jar without disassembly of the parts or interference with the normal uses of the golf bag.

It is a more specific object of the invention to provide a golf bag having a thermos jar supporting and carrying means associated therewith so constructed that the beverage dispensing spigot or valve will be shielded against damage during normal use of the golf bag.

It is also an object of the invention to provide means for receiving and holding a drinking cup during the dispensing of a beverage from the thermos jar without any interference with the normal uses of the golf bag.

Other and more specific objects and advantages of the present invention will appear as the description thereof proceeds. The invention will be described in connection with the accompany-

2

ing drawings forming a part hereof, and in which:

Figure 1 constitutes a top plan view of the golf bag of the present invention with certain parts shown in section;

Figure 2 is a side elevation of the golf bag with certain parts broken away and illustrating the beverage access flap in open position;

Figure 3 is a detailed cross-sectional view along the line 3—3 of Figure 2;

Figure 4 is a transverse cross-sectional view along the line 4—4 of Figure 2;

Figure 5 is a plan view of an alternative embodiment;

Figure 6 is a side elevational view of the embodiment of Figure 5 with certain parts broken away for clarification of illustration;

Figure 7 is a cross-sectional view along the line 7—7 of Figure 6, and

Figure 8 is a detailed showing of a suitable modified form of a thermos jar container for employment in association with the golf bag of the present invention.

Referring to Figures 1 and 2, the main body 25 of the golf bag is shown at 10 and is provided with a rigid bottom section 11 which may be appropriately reinforced to insure retention of the cross sectional configuration of the bag. In the embodiment of Figures 1 and 2, the top of the

30 bag is provided with a continuous reinforcing strip 12 extending completely around the top of the bag wall 10. For the purpose of retaining the individual clubs in proper and predetermined position in the bag, an elongated strip 13 is pro-

35 vided anchored at one end as shown at 14 and at its opposite end as indicated at 15 (Fig. 1). The strip 13 is formed into individual loops 16 and is secured to the bag wall through the medium of suitable adhesive or stitching at the intermediate

40 points as indicated at 17. In this way, each loop 16 provides an individual receiving and supporting means for a single club of the set. The shaft of the club can be readily passed down through the selected loop 16 and the club held in predetermined position in the bag.

The bag shown in the drawings is of a narrower configuration on the side adjacent the carrying strap 18 and handle 19 than at the opposite or remote side of the bag. Indeed, the main wall 10 of the bag converges as indicated at 20 and 21 in Figure 1 in such manner as to provide a substantially semicircular rear wall 22, the diameter of this semicircle constituting the shortest transverse dimension between the straight side walls 55 of the bag.

Coming now to a description of the thermos jar receiving means, it will be observed by reference to Figure 1 that a casing 23 is provided having a cylindrical central compartment 24 which is eccentrically located with reference to the circular portion 22 of the golf bag wall. This eccentric positioning of the cylindrical opening 24 is occasioned by the fact that the casing 23 is so constructed as to provide the substantially radially extending shoulders or walls 25 and 26 defining the vertical channel 27 through which the spigot or faucet 28 at the bottom of the thermos jar 29 may freely pass. These ribs 25 and 26 provide protection for the spigot 28 and insure against the same being broken off or damaged in the normal use of the golf bag.

The casing 23 is secured to the semicircular portion 22 of the wall 10 of the golf bag throughout the area of contact between said wall 22 and the casing 23. The casing 23 may be formed of metal or some molded, rigid plastic material. The bond between the circular wall portion 22 of the wall bag 10 and the casing 23 is preferably provided through the medium of an effective adhesive appropriate for the bonding of metal to leather, fabric, and the like. A urea formaldehyde resin type adhesive has been found practical but it will be appreciated that the particular composition of the adhesive employed in the bonding of the casing 23 to the circular portion of the bag wall 10 may be selected from a wide variety of commercially available bonding agents all within the purview of the present invention. The inner wall of the casing 23 is preferably provided with some aligning slots 30 and 31 for receiving complementary ribs carried by the thermos jar to retain the same against relative rotation in the casing 23.

By reference to Figure 3, it will be observed that the casing 23 is provided with a specially formed bottom construction. It is provided with a transversely extending shelf 32 on which the bottom 29 of the thermos jar is adapted to be seated. Below the shelf 32 a complementary bottom portion 33 of the casing is provided and the space between the shelf 32 and the complementary bottom portion 33 serves as a receptacle for a collapsible drinking cup when not in use. At the inner end of the complementary portion 33 of the bottom of section 23 a downwardly extending section 34 is provided which terminates in the transversely extending bottom portion 35, the latter having an upturned rim 36. A drinking cup such as indicated at 37 is adapted to be seated on the transverse bottom portion 35 and is readily accommodated below the bottom of the thermos jar 29 and the spigot or faucet 28. This faucet 28 is suitably provided with a spring-pressed valve member 38 which may be readily depressed to open the valve and permit the beverage to flow from the thermos jar into the drinking cup 37. Upon release of the valve plunger 38, the valve is immediately closed and the remaining contents of the thermos jar preserved. By virtue of the arrangement for the positioning of the drinking cup 37, immediately below the spigot or faucet 28, none of the beverage is permitted to contact the golf bag or any of the parts thereof and thus any soiling of the bag by the liquid contents of the thermos jar is completely obviated. Access to the spigot 28 and the valve plunger 38 as well as to the drinking cup 37 is had through the access flap 39 shown in open position in Figures 2 and 3. The access flap 39 may advantageously be provided

with a continuous fastener of the "zipper" type as indicated at 40 and 41.

The thermos jar 29 is adapted to be received in a close fitting relationship to the casing 23 and to be frictionally held in assembled position therein with the spigot 28 in a position where it is protected by the walls 25 and 26 of the channel 27 and yet where it is readily available upon opening the access flap 39. The drinking cup is likewise frictionally held between transverse walls 32 and 33 until it is desired for use when it is removed and expanded as shown in Figure 3. When the player has satisfied his thirst, the drinking cup is collapsed and restored to its storage position between the walls 32 and 33. The access flap 39 is closed and the continuous fastener element 40 moved from the position shown in Figure 2 to the position occupied thereby as shown in Figure 1. It will be observed that there is thus provided a means for receiving and carrying a thermos jar containing a beverage responding to the demands of the season as well as the whims or tastes of the player in such relationship to the golf bag and the clubs contained therein as to permit ready access to the beverage container and without in any way contaminating the golf bag or clubs or interfering with the conventional use thereof.

An alternative embodiment is shown in Figures 5 to 7. In this embodiment the casing 23a has concentric inner and outer walls and is provided with a vertically extending slot 27a for the spigot 28. In this embodiment the bag wall 10 is also slotted as indicated at 42. The combined thickness of the bag wall 10 and the wall of the casing 23a functions to protect spigot 28a against damage. In this case the spigot 28a is moved downwardly through the coinciding slots 27a and 42 until the spigot 28a is in its lowest position. A closure and reinforcing flap 43 is provided which is appropriately hinged and secured to the bag wall 10 along the vertical line as indicated at 44. It is highly desirable to provide the closure flap 43 with a steel reinforcing element for bridging the slot 42 in bag wall when the closure flap 43 is in closed position to thereby give rigidly to the bag wall and compensate for the slotting thereof at 42. The closure flap 43 may be provided with snap fasteners such as shown at 45 for securing the same in closed position. When access to the spigot 28a is desired, the snap fasteners are loosened and the closure flap 43 turned back. In this modification the drinking cup 46 is not of the collapsible type and is normally housed and held in position by the bottom wall 47 of the casing 23a. In other respects the embodiment of the modification of Figures 5 to 7 corresponds to that of Figures 1 to 4 and the mode of operation and use of the device is the same.

In Figure 8 there is illustrated a form of thermos jar construction which is readily adapted for use with the present invention. In this case a disc 48 is mounted on the vertical movable valve plunger 49 in such a position that when the drinking cup 50 is pressed upwardly against the disc 48, the discharge valve in the bottom of the thermos jar will be opened and the beverage will flow from the thermos jar into the drinking cup until such time as the pressure applied to the disc 48 is released whereupon the valve will automatically close. It will be appreciated that this is an alternative form of structure appropriate to the present invention in that it positions the discharge valve from the thermos jar so that the same is always pro-

tected against injury or damage in the conventional use of the golf bag. It will be observed that in all modifications of the invention, provision is made to safeguard the discharge valve from the thermos jar against damage incident to the normal use of the golf bag while at the same time permitting ready access thereto when desired.

Having thus described the invention, what we claim is:

1. A golf bag comprising an elongated bag closed at the bottom and open at the top, said bag having a configuration such that a portion of the bag wall constitutes a substantial semicircle, the diameter of which is the shortest transverse dimension between the straight side walls of the bag, a cylindrical casing having an outer diameter equal to the diameter of said semicircular portion of the bag wall and adhered to said bag wall throughout the semicircular area of contact therewith, an access flap carried by the bag wall adapted to be opened to permit access to the lower portion of said cylindrical casing.

2. A golf bag comprising an elongated bag closed at the bottom and open at the top, said bag having a configuration such that a portion of the bag wall constitutes a substantial semicircle, the diameter of which is the shortest transverse dimension between the straight side walls of the bag, a substantially cylindrical casing having an outer diameter substantially equal to the diameter of said semicircular portion of the bag wall throughout the semicircular area of contact therewith, an access flap carried by the bag wall adapted to be opened to permit access to the lower portion of said cylindrical casing.

3. A golf bag comprising an elongated bag closed at the bottom and open at the top, said bag having a configuration such that a portion of the bag wall constitutes a substantial semicircle, the diameter of which is the shortest transverse dimension between the straight side walls of the bag, a cylindrical casing having an

outer diameter equal to the diameter of said semicircular portion of the bag wall and adhered to said bag wall throughout the semicircular area of contact therewith, a longitudinally extending slot in the wall of said casing, an access flap carried by the bag wall adapted to be opened to permit access to the cylindrical casing through said slot.

4. A golf bag adapted to be provided with beverage carrying and dispensing instrumentalities, comprising an elongated bag closed at the bottom and open at the top, said bag having a configuration such that a portion of the bag wall constitutes a substantial semicircle, a cylindrical casing having an outer diameter substantially equal to the diameter of said semicircular portion of the bag wall and adhered to said bag wall throughout the semicircular area of contact therewith, a longitudinally extending slot in the wall of said casing having a width adequate to receive a spigot carried by a thermos jar when the latter is inserted into or withdrawn from said casing, an access flap carried by the bag wall adapted to be opened to permit access to a thermos jar spigot when disposed in said slot, and means for supporting a drinking cup substantially within the confines of the bag wall below said cylindrical casing.
